(57) **CLAIM**

The ornamental design for a digital camera, as shown and described.

DESCRIPTION

FIG. 1 is a front, top and right side perspective view of a digital camera showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a front, top and right side perspective view thereof, illustrating the state where the strobe portion alone is popped up; and,

FIG. 9 is a front, top and right side perspective view thereof, illustrating a state where the strobe portion and the sighting mirror are stored.

The broken lines shown in the drawings are for illustrative purposes only and form no part of the claimed design.
